(57) **CLAIM**

We claim the ornamental design for a charger, as shown and described.

DESCRIPTION

FIG. 1 is a perspective view of a charger showing our new design;

FIG. 2 is another perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a left side cross-section view thereof taken along line 9-9 in FIG. 3.

The dash-dot-dash broken lines adjacent shaded areas depict bounds of the claimed design and form no part of the claimed design. The dash-dash broken lines adjacent shaded areas depict bounds of the claimed design and features of the charger that form no part of the claimed design. All other broken lines depict features of the charger that form no part of the claimed design.

1 Claim, 9 Drawing Sheets
